UNITED STATES PATENT OFFICE.

EDWARD B. T. SCHUMACHER, OF DETROIT, MICHIGAN, ASSIGNOR TO JOHN J. BAGLEY & COMPANY, OF DETROIT, MICHIGAN, A CORPORATION OF MICHIGAN.

COMBINED PIPE AND MATCH HOLDER FOR TOBACCO-JARS.

1,169,198.

Specification of Letters Patent.

Patented Jan. 25, 1916.

Application filed October 16, 1914. Serial No. 867,030.

To all whom it may concern:

Be it known that I, EDWARD B. T. SCHUMACHER, a citizen of the United States of America, residing at Detroit, in the county of Wayne and State of Michigan, have invented certain new and useful Improvements in Combined Pipe and Match Holders for Tobacco-Jars, of which the following is a specification, reference being had thereto in to the accompanying drawings.

The invention relates to match and pipe holders, and it is the object of the invention to obtain a simple construction which is attachable to a tobacco jar.

15 To this end the invention comprises the construction as hereinafter set forth.

In the drawings: Figure 1 is a perspective view of the attachment showing the jar in dotted lines; Fig. 2 is a similar view showing the manner of engaging the clamping band; and Fig. 3 is a horizontal section.

20 A is a metallic band, which at one or more points is bent to form loops B constituting pipe holders. These loops are preferably of circular form and join with the main band by parallel portions C which are riveted or otherwise secured to each other.

25 D is the match box holder struck up from sheet metal to have the parallel front and back walls E F, bottom G and side flanges H for clamping the box. The holder is attached to the band by providing the latter with return bent hooks I which are engageable with the holder preferably by forming L-shaped slits J in the inner wall thereof, as shown in Fig. 2. This permits of sliding

the hook I into engagement with the flange formed by the L-shaped slit while the band is in engagement with the jar, and the resiliency of the metal is sufficient to produce 40 the clamping effect.

What I claim as my invention is:—

1. The combination with a metallic band for surrounding a jar having returnbent hooks at its opposite ends, of a match box 45 holder struck-up from a single sheet metal blank, having L-shaped slits therein for detachable engagement with said hooks while said band surrounds the jar and forming a tie connection therebetween.

2. The combination of a resilient metallic band for surrounding a jar, and having a loop formed in the intermediate portion thereof constituting a pipe holder, and a match-box holder having L-shaped slits for 55 detachably engaging the ends of said band and forming a tie connection therebetween.

3. The combination with a resilient metallic band for surrounding a jar having returnbent hooked ends and an intermediate 60 portion bent to form a plurality of outwardly-extending closed loops, and a match-box holder struck up from sheet metal having L-shaped slits for detachable engagement with said returnbent hooks and forming a tie connection therebetween.

In testimony whereof I affix my signature in presence of a witness.

EDWARD B. T. SCHUMACHER.

Witness:

JAMES P. BARRY.
